WRAP-AROUND APPARATUS FOR KNITTING MACHINES

Harry Agulnek, Brooklyn, N. Y., assignor to Samuel Mishcon, doing business as Supreme Knitting Machine Co., Brooklyn, N. Y.

Application March 7, 1939, Serial No. 260,378

18 Claims. (Cl. 66—135)

This invention relates to knitting machines adapted for the manufacture of fabric containing vertical stripes, and particularly to circular open-top multiple-feed knitting machines having a hollow needle-retaining cylinder operatively associated with the usual yarn-feeding and needle-actuating elements. This invention is further directed to the so-called wrap-around method of producing vertical stripes, and is an improvement over the structure described in my prior application filed October 3, 1938, Serial No. 232,964, now Patent No. 2,175,238.

It is primarily within the contemplation of this invention to provide a simple, easily fabricated and conveniently located wrap-around device in association with the cylinder of the above-mentioned type of knitting machine whereby fabric with vertical stripes and devoid of floats can be readily produced without materially increasing the size and proportions of the entire machine. This objective I accomplish by utilizing the central space within the cylinder for housing certain wrap-around actuating mechanisms, no portion of the structure constituting my invention extending beyond the confines of the substantially cylindrical wall of main yarn strands extending down from the conventional overhead cones of yarn to the conventional feeding stations about the cylinder.

A further object of the above-mentioned aspect of my invention is to maintain the wrap-around actuating mechanism at or slightly above the top level of the cylinder, the attainment of said objective being accomplished by employing horizontally disposed and substantially radially movable elements adapted to effect the wrap-around motion at predetermined intervals.

It is still a further object of my invention to provide a simple and unitary means for operatively elevating both the wrap-around needles as well as the conventional body-yarn needles to a desired latch-clearing level whereby all needles can take body yarn and the said wrap-around needles can take striping yarn as well.

It is also within the contemplation of this invention to provide a machine for accomplishing the aforesaid functions wherein the vertical striping yarn cones are supported by a stand positioned slightly above the central interior of the needle cylinder and in fixed relation with respect thereto, and so disposed as to be in proper operative position with respect to the cylinder needles whereby one or more of a selected number of yarn strands may be operatively fed to a plurality of stations about the cylinder.

Another object of my invention is to provide stretcher or spreader means for the tubular fabric made on knitting machines and which are adapted to cooperate with means for holding the striping yarn stand in fixed position with respect to the cylinder.

Other objects, features and advantages will appear from the drawings and the description hereinafter given.

Referring to the drawings:

Figure 1 is a vertical fragmentary section of a circular open-top independent latch needle knitting machine, with a stationary cylinder, containing one form of my invention, including a semi-diagrammatic representation of a portion of the fabricated cloth.

Figure 2 is a part sectional plan of Figure 1 taken along line 2—2, showing the position of a portion of the tubular fabric upon the stretcher and within the bifurcated terminal of the holding bracket for the aforesaid stationary portions of my apparatus.

Figure 3 is a fragmentary section of Figure 1 taken along line 3—3.

Figure 4 is a part sectional plan of Figure 1 taken along line 4—4 showing the relative positions of the wrap-around device and actuating mechanisms therefor before an operative actuation has taken place.—certain of the sinker mechanisms being removed for clarity.

Figure 5 is a view similar to Figure 4, showing the position of the parts just prior to the wrap-around operation.

Figure 6 is a view similar to Figures 4 and 5 showing the wrap-around mechanisms in actual engagement, certain of the elements being shown by broken lines to indicate the position of the parts just prior to a completion of an operative cycle.

Figure 7 is a perspective view of a wrap-around bar, constituting an element of my invention, illustrating semi-diagrammatically its operation with respect to a latch needle.

Figure 8 is a semi-diagrammatic representation of a portion of a knitting machine containing a cam element of my invention, the drawing being a development of a portion of a cylinder in operative relation with respect to needle elevating and depressing means.

Figure 9 is an enlarged side elevation showing a wrap-around needle and an adjacent body yarn needle in operative engagement with the duplex elevating cam of my invention.

Figure 10 is a fragmentary vertical section of

a circular knitting machine containing a modified form of my invention.

Figure 11 is a part sectional plan of Figure 10, substantially similar to that of Figure 6, showing certain operative positions of the wrap-around device.

Figure 12 is a fragmentary perspective view of the wrap-around bar employed in the structures of Figures 10 and 11.

10 Figure 13 is an enlarged side elevation showing a modified form of wrap-around needle and adjacent body yarn needle in operative engagement with a conventional elevating cam, and

15 Figure 14 is a semi-diagrammatic representation of a portion of a knitting machine containing a conventional elevating cam and a stitch cam in operative engagement with the needles of Figure 13.

20 In the drawings, the knitting machine illustrated is of conventional structure comprising a stationary cylinder 10 containing a plurality of independent vertically movable latch needles 11 adapted to be operatively actuated by elevating and depressing mechanisms at a plurality of feed stations about the cylinder (not shown on the drawings inasmuch as they are well known in the art), these mechanisms being operatively mounted on cam blocks 12 which are positioned upon the rotatable cam ring 13, this ring being in operative engagement with the gear 14 mounted on shaft 15 connected to suitable driving means not shown. Mounted upon and attached to said cam ring 13 are the vertical columns 16 which support the revolving main yarn stand 17 containing thereon the yarn cones 18. The specific construction shown in the drawings has been chosen merely for illustrative purposes, it being understood that a revolving cylinder type of structure, or a spring beard needle machine, or other design 30 of knitting machine in this general category may be similarly adapted for use with my invention.

35 Extending through the central portion of said yarn stand 17 and through the hollow boss 19 thereof is a central supporting post 20, said post being held in suspended position from the yarn stand 17 by suitable fastening means, illustrated in the drawings as the screw 21. The upper portion of the post has secured thereto, through the medium of screw 22, the yarn guide holding member 23 the guides 23a of which operatively receive the yarn from cones 18, the yarn strands therefrom being directed downwardly towards the cylinder of the machine. Thus, referring to Figure 1, extending downwardly from the guides 23a are 40 a plurality of closely spaced yarn strands 24 forming a frusto conical or substantially cylindrical wall of yarn.

45 At a lower portion of said post 20 is the collar 25 shown secured in place by the set screw 26. 50 Mounted upon said collar 25 is the thrust bearing 27, illustrated as of ball-bearing construction, and surmounted upon said bearing is the stationary dial member 28. Surmounted upon said stationary dial member 28 is the rotatable dial 29, said latter dial being rotatable with respect to the stationary dial in a manner to be more fully hereinafter set forth. It will be noted that the said post or shaft 20 extends through the hubs 30 and 31 of the dials 55 29 and 28 respectively, the lower or stationary dial being rotatably mounted over the shaft and the upper or rotatable dial being in fixed engagement therewith by means of the set screw 32. Suitably mounted upon the top of rotatable dial 29 is the ball-bearing structure 33 which operatively supports the stationary auxiliary yarn

stand 34 supporting the striping yarn cones 35, the number of said striping yarn cones being made to correspond with the number of striping stations about the cylinder, and these in turn correspond with the number of wrap-around devices 5 employed. From the cones 35 strands of yarn are directed to guides 36 from which such strands 37 are carried down to the wrap-around device in a manner to be hereinafter described.

10 The lower or stationary dial member 28 contains a peripheral portion 38 having therein a plurality of substantially radially disposed slots 39 for operatively and slidably accommodating the wrap-around bars 40, as will hereinafter be set forth. And surmounted upon the upper surface 15 of said peripheral portion 38 is the ring-like plate 41 adapted to hold the bars 40 in proper horizontal position, said plate containing recessed portions 42 of sufficient radial length to permit an operative movement of members 40, as will hereinafter appear. The upper or rotatable dial member 29 contains a peripheral portion 43 which is in effect a cam ring containing on the underside thereof the grooved recess 44 (see Figs. 4, 5 and 6) extending substantially circumferentially about 20 peripheral portion 43, said recess having a plurality of sharply curved outwardly extending portions 45 to correspond with the number of body-yarn feed stations employed in the structure. The said cam portion 43 is surmounted upon the 25 plate 41 of the stationary dial 28, so as to be in slidably and rotatable engagement therewith, the grooved portion 44 accommodating the butts 46 of the wrap-around bars 40. Both upper and lower dials contain a plurality of reinforcing ribs 47 and 48 respectively, these ribs extending from the hubs of the dials to the said peripheral portions.

30 The stationary dial member 28 is held against rotation by an arrangement whereby it is locked in fixed relation with respect to the cylinder 10; and if the cylinder is stationary, the locking means can be attached either directly to the cylinder or to any other convenient structural part of the machine to which the cylinder is secured. In the form illustrated, the locking elements consist of the substantially vertical bars 49 attached by bolts 50 to the bosses 51 extending downwardly from the stationary dial 28, and the horizontal arms 52 attached to the lower extremities of bars 49. These arms extend between the bifurcated terminals 53 of the brackets 54 which are attached by bolts 55 to the stationary framework of the machine. The relative proportions of the arms 52 and the corresponding brackets 54 are such as 35 to enable the tube of material 56 to pass therebetween, the bifurcated terminals 53 holding the arms 52 against lateral movement. In this manner it is apparent that the lower dial member 28 is firmly held against rotary movement. Suitably attached to the stationary dial member 28 is the member 57, the lower arm 58 of which is held against lateral movement by the bracket 59. The upper portion of member 57 is attached by bracket 60 to the auxiliary yarn stand 34, thereby likewise 40 holding said yarn stand against movement. The upper dial member 29, being secured by fastening means 32 to post 20, obviously revolves together with the post. And inasmuch as both dials are 45 positioned between bearings 27 and 33, the upper dial member 29 and post 20 will encounter a minimum of resistance to rotation by the fixed and immovable disposition of the stationary dial member 28 and stationary auxiliary stand 34.

50 The wrap-around bar 40 consists of a flat thin 45

vertical strip 61 containing, in the preferred form thereof, a terminal portion 62 twisted at right angles thereto; said latter portion being horizontal and serving as a bearing for the finger 63 rotatably mounted upon the pin 64 secured preferably by nut 65 to the flat terminal portion 62. Surmounted over the shank of pin 64 is the spring 66 containing a terminal portion 67 in engagement with the finger 63 and normally urging said finger 63 in longitudinal alignment with the strip 61. And in the preferred arrangement, finger 63 contains the stop 68 thereon abuttable with portion 62 to prevent a further pivotal movement of finger 63. According to the form illustrated, the finger 63 15 contains at the terminal thereof a single feeding tube 69, although more than one tube may be employed if desired. As many wrap-around bars 40 can be operatively employed as may be required, each of the bars being so positioned that the strips 20 61 are vertically disposed within the radial slots 39 of the terminal portion 38 of the stationary dial 28, and with the butts 46 extending upwardly into the grooved recess 44 of the dial cam ring 42. The tube 69 is normally (in its inoperative position) disposed slightly behind the hook 70 of the adjacent wrap-around needle, this being the position of the tube when the butt 46 is in any portion of groove 44 except the said sharply curved portions 45. The movements of the wrap-around 25 mechanism will be more fully hereinafter explained.

In order to properly effect a wrap-around operation without interrupting the continuity of feeding the body yarn, it is apparent that there 30 must be two sets of needles, one for wrap-around purposes and the other for creating body fabric, the wrap-around needles being elevated to a latch-clearing position above that of the body 35 yarn needles. Although several methods can be employed for selectively elevating the needles to their respective yarn taking levels, such as by means of conventional selector wheels or plate cams adapted for wide butt wrap-around needles, the structure of elevating means which I prefer 40 is that illustrated in Figure 8, where a double-track cam 71 is employed. This cam is of stepped formation, containing an inwardly protruding portion 72 provided at the top thereof with the 45 normal cam surface 73 having an inclination adapted to receive the short butt 74 of the normal 50 body yarn needle 75. Farther removed outwardly from the cylinder with respect to said surface 73 is the wrap-around cam surface 76 of the cam 71, this latter surface being at a slightly steeper elevation and extending to a higher level than surface 73. The surface 76 is out of reach of the 55 butts 74 of the normal body yarn needles but sufficiently close to the cylinder to operatively receive the relatively long butts 77 of the wrap-around needles 78. Positioned above and 60 directly behind the upwardly inclined surfaces 73 and 76 is the stitch cam 79 which is adapted to receive the butts of all the needles for operatively drawing them down. In the preferred structure 65 illustrated, the cam 71 is of duplex structure, containing cam surfaces 73a and 76a equivalent to surfaces 73 and 76, whereby with this construction the needles are again operatively elevated after leaving the stitch cam 79, to begin another 70 cycle, the needles subsequently being drawn down by stitch cam 79a. It is of course understood that any number of cam structures with surfaces equivalent to 73 and 76 may be employed in proper spaced relation about the cylinder.

75 It should further be noted, still referring to

Figure 8, that when the butts 77 of the wrap-around needles 78 reach the uppermost level W of surface 76, the hooks of each of these wrap-around needles are positioned above the hooks of body yarn needles 75 when the butts of said last-mentioned needles reach the uppermost level B of the surface 73. However, the latches 80 of the wrap-around needles are longer than the latches 81 of the body yarn needles, to enable the wrap-around yarn, when being fed from their relatively high feeding positions, to operatively engage the latches 80; for if the latches 81 were shorter there would always be the danger that the wrap-around yarn would engage the shanks of the wrap-around needles below the latches unless the feeding points of such yarn were elevated to a carefully selected excessively high position. It should further be noted that when the needles are in their uppermost positions, the latches 80 and 81 of both the wrap-around and body yarn needles extend above the latch-clearing level 82 illustrated in Figure 8 with reference to the conventional sinker 83.

In the operation of this apparatus, a predetermined number of wrap-around needles 78 are 25 positioned in selected stations about the cylinder, in accordance with the desired design. A corresponding number of wrap-around bars 40 are operatively positioned within the radial slots 39 of the stationary dial 28, these bars being so 30 positioned with respect to the said wrap-around needles 78 that the said tube 69 affixed to each finger 63 of said bars will be slightly behind its corresponding needle 78 and in its normal retracted position closer to the cylinder. In this 35 retracted position, as aforesaid, the butt 46 is positioned within the cam groove 44, but somewhat in advance of the outwardly projecting portion 45 thereof (see Fig. 4). As the upper or rotatable dial 29 rotates in the direction of arrow A, the 40 said projecting portion 45 of groove 44 will approach the butt 46 and will operatively project the bar 40 forwardly into the position indicated in Figure 5. In this position it will be noted that the tube 69 is still in advance of the needle 78 45 with respect to the direction of rotation of the cam ring about the cylinder, and is also projected forwardly of said needle. By a mechanism to be more fully hereinafter set forth, the finger 63 and tube 69 are actuated in the direction of rotation 50 of the elements moving about the cylinder, whereby said tube 69 and the wrap-around yarn carried thereby will be moved in a path across the needle 78, as indicated in Figure 6; and thereafter the entire bar 40 is retracted by the grooved path 44 after the projecting curved portion 45 thereof 55 will have passed butt 46, thereby completing an entire wrap-around operation.

Rotatably mounted about the cylinder 10 is the conventional sinker cam ring 84 for radially moving the sinkers 83 into their respective projected and retracted positions. Suitably mounted upon said cam ring 84 and obviously rotatable therewith are a plurality of spaced cams 85 corresponding in number with the body-yarn stations, these cams projecting inwardly towards the cylinder and being adapted to engage the fingers 63 of said bars 40 when the bars are in their projected positions as indicated in Figures 5 and 6. 65 The said sinker cam ring 84 rotates together with the cam ring 13, posts 16, main yarn stand 17, post 20 and the upper rotatable dial 29, so that there can readily be a cooperative relation between protruding portions 45 of cam slot 44 and 70 75

the cams 85 whereby they can both operatively actuate the bar 40.

It is thus apparent that as the cam ring 84 and the rotating dial 29 revolve about the cylinder, the wrap-around bars 40 will be projected forwardly by the walls of cam groove 45, and the fingers 63 engaged by cams 85 will be swung in the direction of rotation of the sinker cam ring, bringing the yarns 37 around the shanks and latches of needles 78. Referring to Figure 6, the position of the cam 85 and tube 69 is shown during the retraction of bar 40; and it is obvious that after the tube 69 is retracted further inwardly (cam 85 now being out of engagement with finger 63), the spring 66 will bring the finger back to its normal position as indicated in Figure 4. During this retraction, the tube 69 will be sufficiently inwardly disposed to entirely clear needle 78. The approximate direction of movement of tube 69 is indicated in Figure 7 wherein the wrap-around yarn is shown formed into several loops constituting the striped portion of the fabric.

As the cam ring 13 and associated parts continue their rotary movement about the cylinder, the body yarn 24 will be operatively received by the various needles to produce the body portion of the knitted fabric; and this operation takes place with the wrap-around needles preferably just after the wrap-around step has been completed. All needles are subsequently drawn down by the stitch cams to complete a knitting cycle. Thus in Figure 7, the striping yarn 37 is shown as an integral part of a fabric containing the body yarn 24.

As indicated in Figure 8, the wrap-around and body yarn needles are elevated to their respective levels by the cam 71, the uppermost positions of all the needles being such that the latches are always above latch clearing position.

It should further be noted that the fabricated cloth 56, extending downwardly from the cylinder in tubular form, passes between the bifurcated terminals 53 of the bracket 54 and the outer terminals of the arms 52. As the arms 52 extend outwardly just short of the cylinder, they serve the additional function of spreaders for the tubular fabric.

During the rotary movement of the various parts above-described, the lower dial 28 is at all times stationary, being held in that position by the vertical bars 49 and arms 52; and the auxiliary striping yarn stand 34 is similarly held in a stationary position by the member 57, all as hereinabove clearly set forth. Hence the structure provides a convenient means of enabling the wrap-around yarn to be operatively fed at desired stations about the cylinder, in cooperative relation with ordinary body yarn operatively knitted through the medium of the rotating mechanisms. A considerable portion of the wrap-around apparatus is positioned within the hollow interior of the cylinder, which is normally unutilized space; and no portion of the wrap-around mechanism nor the stand for the wrap-around yarn extends outside of the machine, nor in fact outside of the substantially cylindrical wall of body yarn 24.

An important feature is the construction hereinabove described embodying the employment of radially movable wrap-around bars 40, these bars being substantially at the level of the needles, or just slightly thereabove. This construction removes the objection of most other devices wherein there are vertical actuators extending considerably above the cylinder rendering such devices

cumbersome and dangerous. The simplicity and ease of action of the present invention is rendered possible by the use of the relatively simple and horizontally disposed dial members, one being rotary and the other stationary.

It is also within the contemplation of my invention to enable the objectives thereof to be efficiently accomplished not only in the manner above-described, but also by a relatively simpler method, whereby both or either the aforesaid radially moveable wrap-around bars 40 and the double-track cams 71 may be dispensed with. By referring particularly to Figures 10, 11, and 12, it will be seen that instead of employing the said radially movable bars, the stationary wrap-around bars 90 are used, these being suitably mounted at selected stations along the periphery of the stationary dial-like platform 91. This platform is held in fixed relation with respect to the cylinder 10 by holding means 49a similar to those employed in the aforesaid preferred structure of my invention. Each of the said bars 90 is provided with a pivotally mounted flap or finger 92, held by spring 93 in predetermined fixed relation with respect to the body portion of bar 90. The said flap contains therein an aperture 94 for receiving the wrap-around yarn 95 from the yarn cones 96 which are preferably, although not necessarily, positioned on platform 91. In the preferred arrangement, the wrap-around bar 90 is provided with an upright portion 97 containing an aperture 98 therein for receiving the yarn 95 and enabling it to be properly guided to the said aperture 94.

Suitably mounted upon the cam ring 84 and obviously rotatable therewith are a plurality of spaced cams 99, analogous in function to the cams 85 of the preferred structure above-referred to, these cams corresponding in number with the body-yarn feed stations. Each of the cams 99 extends inwardly towards the cylinder and is adapted to engage the adjacent flap 92 of the bar 90 during the rotary movement of the cam ring, each cam 99 swinging the coating flap 92 against the action of spring 93 to its projected wrap-around position.

Specifically, by referring to Figure 11 it will be seen that the cam 99 strikes the flap 92 and carries it to the position indicated by dash lines. When this action occurs, the wrap-around yarn 95 is carried around the shank of the wrap-around needle 100, as indicated in Figure 11; and thereafter when the needle is operatively depressed, the wrap-around yarn will be operatively carried downwardly by the hook of the needle. Obviously, when the cam 99 passes beyond flap 92 in its projected position, the flap will be returned to its normal position under the influence of the spring 93. It has been found that a complete wrap-around swing can thus be satisfactorily effectuated, without any radial movement of the bar 90.

By referring to Figures 13 and 14 it will be seen that instead of employing the double-track cam equivalent to cam 71 illustrated in Figures 8 and 9, the conventional elevating cam 101 and stitch cam 102 are employed. The wrap-around needle 103, however, contains a high butt 104, the distance X from the top of the said high butt to the top of the needle being equal to the distance Y from the top of the conventional butt 105 of the conventional needle 106 to the top of said needle.

During the operation of the machine, the needles 103 and 106 are elevated by the cam 101,

the wrap-around needle 103 being obviously elevated to a higher position than the conventional needles, so as to enable the wrap-around operation to be effectuated in a manner similar to that described with reference to the structure of Figures 8 and 9. The uppermost level of both the conventional and wrap-around needles is above latch-clearing. When the cam 102 operatively reaches the butts of both the conventional and wrap-around needles, it will depress all of said needles to the same lowermost cast-off level K, inasmuch as the distances of both types of needles above their respective butts are equal. It is thus obvious that with the arrangement illustrated in Figures 13 and 14, the double surface cam 71 can be dispensed with.

It is of course understood that the structures above-described and shown in the drawings are illustrative of my invention and not employed by way of limitation, inasmuch as numerous changes and modifications may be made therein within the scope of the appended claims without departing from the spirit of this invention.

What I claim is:

25 1. In a circular open top knitting machine an open-ended needle cylinder, a main yarn stand positioned above the cylinder for operatively holding body yarn cones in predetermined positions with respect to selected feeding stations 30 about the cylinder, means for bringing the yarn from said cones into operative engagement with the needles on the cylinder, an auxiliary yarn stand between the cylinder and the main yarn stand, said auxiliary stand being adapted for 35 operatively supporting vertical striping yarn cones in fixed predetermined positions with respect to the cylinder, feeding means adjacent selected needles on the cylinder for operatively bringing the yarn from the cones on said auxiliary stand into operative engagement with said selected needles, actuators for said feeding means and movable within a substantially horizontal plane, supporting means for holding said actuators during their operative movements in substantially horizontal positions, said supporting means being in fixed relation to the cylinder, a 40 sinker cam ring exteriorly disposed with respect to the top of the cylinder, and cam means mounted upon said cam ring, said cam means projecting inwardly a sufficient amount for operative engagement with said actuators during the operative movement of the rotary portion of the machine.

2. In a circular open top knitting machine 55 an open-ended needle cylinder, a main yarn stand positioned above the cylinder for operatively holding body yarn cones in predetermined positions with respect to selected feeding stations about the cylinder, means for bringing the yarn from said cones into operative engagement with the needles on the cylinder, an auxiliary yarn stand between the cylinder and the main yarn stand, said auxiliary stand being adapted 60 for operatively supporting vertical striping yarn cones in fixed predetermined positions with respect to the cylinder, feeding means adjacent selected needles on the cylinder for operatively bringing the yarn from the cones on said auxiliary stand into operative engagement with said selected needles, actuators for said feeding means and movable within a substantially horizontal plane, supporting means for holding said actuators during their operative movements in substantially horizontal positions, said supporting 65

means being in fixed relation to the cylinder, means for operatively moving said actuators into inner retracted positions and outer projected positions, and a sinker cam ring exteriorly disposed with respect to the top of the cylinder; the said actuators constituting wrap-around elements each having a pivotally mounted finger carrying the said feeding means, the feeding means being behind their respective cooperating needles when their respective actuators are in their retracted positions and in front of said needles when the actuators are in their projected positions; and further provided with cam means mounted on said cam ring for operatively engaging the said fingers, during the operative movement of the machine, to move the feeding means carried by the fingers past the adjacent cooperating needles, whereupon the corresponding striping yarn will be operatively wrapped about the adjacent needle upon a retraction of the actuator.

3. In a circular knitting machine, a hollow needle-retaining cylinder, body-yarn needles and wrap-around yarn needles at spaced intervals about the cylinder, needle-elevating and needle-depressing means, the needle-elevating means including means to raise the needles to latch-clearing positions with the hooks of the wrap-around needles above those of the body-yarn needles, the needle-depressing means being engageable with all the needles, a main yarn stand positioned above the cylinder for operatively holding body yarn cones in predetermined positions, means for bringing the yarn from said cones into operative engagement with the said body-yarn needles, an auxiliary yarn stand for operatively supporting vertical striping yarn cones in fixed predetermined positions with respect to the cylinder, feeding means adjacent selected needles on the cylinder for operatively bringing the yarn from the cones on said auxiliary stand into operative engagement with said wrap-around needles at points above the feeding level of the body-yarn, substantially horizontally disposed actuators for said feeding means and movable from normal retracted positions to projected positions, substantially horizontal supporting means for said actuators and in fixed relation with respect to the cylinder, and means for operatively moving said actuators, the latches 50 of the wrap-around needles being longer than those of the body-yarn needles, the latches of all needles when open at their uppermost positions being above latch-clearing level.

4. In a circular knitting machine, the combination according to claim 3, the butts of the wrap-around needles being longer than those of the body-yarn needles, and the said elevating means comprising a plurality of double-track cams each containing two inclined surfaces, one 60 of said surfaces being relatively close to the cylinder and adapted to operatively engage only the short butts of the body-yarn needles, the other of said surfaces being farther removed from the cylinder and out of reach of the said 65 short butts and adapted to engage only the long butts of the wrap-around needles and also being of a greater height and steeper inclination than said first-mentioned inclined surface.

5. In a circular knitting machine adapted to 70 operatively accommodate long-butt and short-butt needles, a unitary elevating cam member comprising a plurality of spaced double-track sections, each of said sections containing an inwardly protruding portion provided at the top 75

- thereof with an inclined cam surface for operatively engaging only the short-butt needles, and an outer portion more remote from the cylinder than said inwardly protruding portion and provided at the top thereof with an inclined cam surface out of reach of the short-butt needles and adapted to operatively engage only the long-butt needles, said two cam surfaces being of different inclinations and heights; and a stitch cam following each of said sections for operatively engaging the butts of all the needles to draw them down; the said cam members containing a recessed portion between said double-track sections for accommodating a coacting stitch cam.
15. 6. In a circular open top knitting machine, a stationary open-ended needle cylinder, a rotatable main yarn stand positioned above the cylinder for operatively holding body yarn cones in predetermined positions with respect to selected feeding stations about the cylinder, means for bringing the yarn from said cones into operative engagement with the needles on the cylinder, a stationary auxiliary yarn stand between the cylinder and the main yarn stand and adapted for operatively supporting vertical striping yarn cones in fixed predetermined positions with respect to the cylinder, a central post keyed to the main yarn stand so as to revolve therewith and extending downwardly axially of the cylinder, a stationary dial loosely mounted over said post and positioned adjacent the top of the cylinder and in fixed relation with respect thereto, said dial having a substantially horizontal peripheral portion adjacent the interior of the cylinder, a plurality of substantially radially disposed wrap-around bars mounted upon said peripheral portion, feeding means associated with said bars operatively connecting the yarn from said auxiliary stand to selected adjacent coacting needles.
20. 40. about the cylinder, each of said bars containing an upwardly extending butt, and a rotatable actuator dial keyed to said central post and revolvable therewith, said actuator dial having a peripheral cam portion superimposed upon said stationary dial and engageable with said butts for operatively projecting and retracting the bars and their associated feeding means into predetermined operative positions with respect to their respective coacting needles.
25. 50. 7. In a circular open-top knitting machine, the combination according to claim 6, the said central post having affixed thereto a bearing in supporting engagement with said stationary dial, other bearing means superimposed upon said rotatable dial and in supporting engagement with said auxiliary stand, and means for holding said auxiliary stand in fixed relation to the cylinder.
30. 55. 8. In a circular open-top knitting machine, the combination according to claim 6, the peripheral portion of the stationary dial containing a plurality of radially disposed slots for accommodating said bars, and the peripheral portion of the rotary dial containing on the underside thereof a recessed cam portion into which the butts of the said bars operatively extend.
35. 60. 9. In a circular open-top knitting machine, a wrap-around bar comprising an elongated strip, a finger pivotally mounted on said strip, a yarn-feeding tube secured to said finger, spring means yieldably holding said finger in a predetermined normal position with respect to said strip, a butt protruding from said strip, means for supporting said strip substantially horizontally and radially with respect to the cylinder of the machine and adjacent the open top thereof, actuating means

for engaging said butts for operatively actuating the bars into predetermined positions with respect to selected needles on the cylinder, and cam means associated with the cylinder for engaging said fingers for pivotally moving them against the resistance of said spring means into predetermined positions with respect to said selected needles.

10. 15. A wrap-around bar for operative use with a selected needle on a circular open-top knitting machine, comprising an elongated strip containing a butt protruding therefrom, a finger pivotally mounted on said strip, a spring yieldably holding the finger in a predetermined position with respect to the strip, and a yarn-feeding tube secured to said finger.

11. 20. A wrap-around bar for operative use with a selected needle on a circular open-top knitting machine, comprising a flat thin strip having a terminal position twisted at right angles thereto, a finger pivotally secured to said terminal portion, a spring yieldably holding the finger in substantial longitudinal alignment with said strip and a yarn-feeding tube secured to said finger.

12. 25. In a circular open top knitting machine, an open-ended needle cylinder, a main yarn stand positioned above the cylinder for operatively holding body yarn cones in predetermined positions with respect to selected feeding stations about the cylinder, means for bringing yarn from said cones into operative engagement with the needles on the cylinder, a central post secured to the main yarn stand and extending downwardly axially of the cylinder, a dial-like platform loosely mounted over said post and positioned adjacent the top of the cylinder and in fixed relation with respect thereto, a predetermined number of vertical striping yarn cones in fixed predetermined positions with respect to the cylinder, said platform having a substantially horizontal peripheral portion adjacent the interior of the cylinder, a wrap-around bar for each of said striping yarn cones mounted on said peripheral portion, feeding means associated with each of said bars operatively connecting the yarn from said striping yarn cones to selected adjacent coacting needles about the cylinder, each of said bars containing a pivotally mounted finger and a spring yieldably holding the finger in fixed predetermined relation to the body portion of the bar, and cam means associated with the cylinder for engaging said fingers for pivotally moving them against the action of said springs into predetermined positions with respect to said selected coacting needles.

30. 35. 50. 55. 60. 65. 70. 75. 13. In a circular open top knitting machine, the combination according to claim 12, wherein the bars are stationary except for the said fingers, each of said fingers being adapted to slidably support a yarn from a corresponding striping yarn cone, said fingers each being normally on a predetermined side of an adjacent coacting needle and being adapted to be actuated by said cam means on the cylinder to a projected position on the opposite side of said needle, whereupon the corresponding striping yarn will be operatively brought into engagement with said needle under the hook thereof.

14. 70. 75. A wrap-around bar for operative use with a selected vertical needle on a circular open-top knitting machine, comprising a horizontally extending elongated strip, a horizontally extending finger pivotally mounted on said strip, and a spring yieldably holding the finger in a predetermined position with respect to the strip.

15. A wrap-around bar for operative use with a selected needle on a circular open-top knitting machine according to claim 14, the finger having an apertured feeding portion for slidably receiving a yarn therethrough.
16. A wrap-around bar for operative use with a selected needle on a circular open-top knitting machine comprising an elongated strip, a finger pivotally mounted on said strip, and a spring yieldably holding the finger in a predetermined position with respect to the strip, the finger having an apertured feeding portion for slidably receiving a yarn therethrough, further provided with an upright portion containing an aperture therein for slidably receiving yarn therethrough and guiding it to said apertured feeding portion on the finger.
17. In a circular open top knitting machine, the combination according to claim 12, the said selected coacting needles being wrap-around needles and all the other said needles being body yarn needles, the cylinder being further provided with needle elevating and needle-depress-

- ing means, the needle-elevating means including means to raise the needles to latch-clearing positions with the hooks of the wrap-around needles above those of the body-yarn needles, the needle-depressing means being engageable with all the needles.
18. In a circular open top knitting machine, the combination according to claim 12, the said selected coacting needles being wrap-around needles and all the other said needles being body 10 yarn needles, the cylinder being further provided with needle-elevating and needle-depressing means, the needle-elevating means including means to raise the needles to latch-clearing positions with the hooks of the wrap-around needles 15 above those of the body-yarn needles, the needle-depressing means being engageable with all the needles, the butts of the wrap-around needles extending higher than the butts of the body-yarn needles, the shanks of all the needles from the 20 tops of their respective butts to the hooks thereof being substantially the same height.

HARRY AGULNEK.
